UNITED STATES PATENT OFFICE

FRED W. LA CHANCE, OF CHICAGO, ILLINOIS

PRICE POSTING MACHINE

Application filed April 25, 1930. Serial No. 447,352.

This invention relates to a novel price posting machine and consists of a novel combination of elements arranged to form a machine which will be simple in construction and efficient and rapid in operation.

The salient object of my invention is to provide a machine in which the prices of a multiplicity of articles may be arranged for expeditious selection and which may be, after selection, imprinted at proper places on invoices, inventories, and analogous accounting statements. This is done manually at the present time and the work is checked by an additional group of employees. This entails considerable expense and errors are frequent because of the human element involved.

Therefore, another object of the invention is to so arrange the device that the desired set of prices may be expeditiously selected and imprinted in a rapid and accurate manner.

Another object of the invention is to so arrange the sets of prices that they may be aligned with the sheets to imprint the prices thereon at the proper places.

An object, ancillary to the foregoing, is to so imprint the prices that checking thereof will be facilitated.

Another object of the invention is to so arrange the device that a selected set of prices may be caused to imprint in any desired number of times.

A further object of the invention is to so construct the device that certain portions may be operated in different directions, while other portions operate in a continuous direction.

A still further object of the invention consists in so arranging the parts that operation of the various parts may be caused to occur at definite times during the cycle of operation.

A still further object of the invention resides in so constructing the device that operation thereof will be substantially noiseless and so that shocks and strains will be dissipated in order that wear and likelihood of breakage will be reduced to a minimum.

Other objects will appear hereinafter.

The invention consists in the novel combi-

nation and arrangement of parts to be hereinafter described and claimed.

The invention will be best understood by reference to the accompanying drawings showing the preferred form of construction, 55 and in which:

Fig. 1 is a front elevational view of a preferred embodiment of my invention in which certain parts are broken away;

Fig. 2 is a side elevational view of the embodiment of my invention illustrated in Fig. 1;

Fig. 3 is a fragmental plan view of the rear portion of the device;

Fig. 4 is a fragmental plan view of the 65 front portion of the device;

Fig. 5 is a view looking in the same direction as Fig. 1 in which the selecting mechanisms and other appurtenances on the front portion of the machine are broken away;

Fig. 6 is a fragmental view looking in the same direction as Fig. 2 depicting certain of the operating elements;

Fig. 7 is a detail view illustrating intermittent driving mechanisms employed in the 75 device;

Fig. 8 is an elevational view of the type carrier employed in the device;

Fig. 9 is a sectional detail view taken substantially on the plane of the line 9—9 on 80 Fig. 8;

Fig. 10 is a sectional detail view taken substantially on the plane of the line 10—10 on Fig. 8;

Fig. 10A is a detail view of the wedging spacer employed in the type bar mounting;

Fig. 11 is a sectional detail view illustrating the type positioning mechanism;

Fig. 12 is a detail view illustrating one 90 form of ledger sheet with which the device is used;

Fig. 13 is a perspective detail view of the selecting indices;

Fig. 14 is a plan view of the parts illustrated in Fig. 13;

Fig. 15 is a detail side view of the key operating mechanism employed in the device;

Fig. 16 is a detail side view of the mecha- 100

nisms illustrated in Fig. 15 looking in an opposite direction;

Fig. 17 is a detail view illustrating the operating keys;

Fig. 18 is a detail view of the carriage mechanism taken substantially on line 18—18 of Fig. 5;

Fig. 19 is a fragmentary detail view of certain parts of the key operating mechanism;

Fig. 20 is a plan view of the same;

Fig. 21 is a fragmentary rear elevational view of the cam shown in Fig. 6;

Fig. 22 is an elevational side view of the device employed to cause the imprinting;

Fig. 23 is a detail view taken substantially on line 23—23 of Fig. 22;

Fig. 24 is a detail view taken substantially on the plane of the line 24—24 on Fig. 4;

Fig. 25 is a plan view of the same.

Fig. 26 is an end detail view of the mechanism shown in Fig. 27;

Fig. 27 is a fragmental view of certain of the mechanisms taken substantially on line 27—27 of Fig. 3; and

Fig. 28 is a detail view taken substantially on the line 28—28 on Fig. 3.

The preferred form of construction for my invention is shown in the accompanying drawings. Therein, 10 indicates the base upon which the entire structure is mounted. As is shown best in Fig. 3, an electric motor 11 is mounted on the base 10 along the rear edge thereof. In this instance the motor 11 includes a shaft 12 which extends in both directions therefrom. This motor 11 drives the entire device and suitable connections between the operating parts and the motor are provided which include, in part, the following mechanisms.

On the end 12' of the shaft 12 spaced apart gears 13 and 14 are keyed. Extending up from the base 10 and secured thereto are the spaced apart brackets 15 and 16 in which bearings 17 and 18 are formed. A shaft 19 is retained in these bearings and rotatably mounted thereon is the gear 20 which meshes with and which is driven by the gear 13. It is to be noted that at the end 12'' of the shaft 12' an identical construction to that described is provided which includes the gears 13' and 20' and the above described allied parts. Similar parts in these constructions are indicated by similar numbers, the numbers of the parts co-operating with the end 12'' being primed. The gear 14 meshes with a pinion 21 that is keyed on the shaft 22 which is journaled in the bearings 23 and 24 formed in the brackets 25 and 26 that are secured to the base 10. Meshing with the pinion 21 is a gear 27 that is rotatably mounted on the shaft 19. This construction is such that the gears 20 and 27 freely rotate in opposite directions on the shaft 19.

Mounted on the shaft 19 and disposed between the gears 20 and 27 are the pulleys 28

and 29 which have hub portions 30 and 31 formed thereon that are disposed to extend toward each other.

By referring to Figs. 3, 27 and 26 it may be seen that these hub portions are grooved so as to receive the arms 32 of the shifting fork 33. The shifting fork 33 is carried by the rod 34 which is journaled in structures such as 35 and 35' which are carried by the base 10 (Fig. 3).

As is clearly shown in Fig. 3, on gear 27' a plurality of laterally extending pins 40' are provided which are disposed in circular formation on the portion of the hub thereof that is disposed toward pulley 29'. Similarly disposed recesses 41' are provided in the hub of pulley 29', Fig. 27. When the rod 34 is rocked, in a manner to be described, so as to move shifting fork 33', the pulley 29' will be moved toward gear 27' and the pins 40' will enter the recesses 41' and thus the pulley 29' will be connected to gear 27'. A similar construction is provided for connecting the pulley 28' and the gear 20' and, as depicted these elements are in disengaged position. A similar construction is provided for connecting the gear 20 and the pulley 28 as well as for connecting the gear 27 and the pulley 29. As will be brought forth hereinafter, the pulleys 28 and 28' are adapted for rotation at the same time and the pulleys 29 and 29' are likewise adapted for simultaneous rotation. In order to accomplish this it is necessary that the rods 34 and 34' be interconnected and that these rods move in opposite directions. This condition is taken care of by the following structure.

The rods 34 and 34' extend to the front of the machine and on the ends thereof the operating handles 42 and 42' are mounted. On the rods 34 and 34' in front of the structures 35 and 35', connectors 43 and 43' are adjustably mounted. Mounted on the base 10 substantially midway between the rods 34 and 34' is the bracket 48. (Figs. 3 and 28.) The bracket 48 has a bearing 49 in which the stud shaft 50 is rotatably journaled. On the rear end of the shaft 50 a connector 51 is provided to which the inner end on the link 45 is attached. The link 45 is attached to connector 43 in the same manner as link 45' is attached to connector 43'. On the opposite end of shaft 50 a connector 52 is provided and the link 45' is attached thereto. Thus, when rod 34 is moved in one direction by manipulation of handle 42, rod 34' is moved in the opposite direction. A similar action results when handle 42' is manipulated.

From the foregoing it is apparent that the gears 20', 27', 20 and 27' rotate continually when the motor 11 is operating. The gears 20 and 20' rotate in one direction and the gears 27 and 27' rotate in the opposite direction. Further, it has been pointed out that the pulleys 28, 29, 28' and 29' may be selec-

tively engaged with the just named gears and when the pulleys are engaged as described they will rotate with the gears. This action is utilized to drive certain parts of the machine, selectively, in different directions.

In Fig. 2 it is shown that the device includes a frame 53 and that oppositely disposed brackets such as 54 are supported from the upper portion of said frame 53. Bearings 56 and 57 are provided in the brackets 54, and the shafts 58 and 59 are rotatably journaled in these bearings. Fixedly mounted on the shafts 58 and 59 are the drums 60 and 61. Pulleys 62 and 63 are freely mounted on shafts 58 and 59 and are disposed between the ends of drums 60 and 61 and the brackets 54. Corresponding pulleys are similarly mounted at the opposite ends of the drums, as shown in Fig. 4, wherein the pulleys 63 and 63' are depicted. The pulleys just described are connected to the shafts on which they are mounted in a manner to be set forth presently. A belt 64 extends between the pulleys 63 and 29 and a belt 64' extends between pulleys 63' and 29'. Similar belts 65 and 65' extend between pulleys 62 and 28 and pulleys 62' and 28'. Since pulleys 29 and 29' operate in a direction opposite to that of pulleys 28 and 28' and, as set forth, since these sets of pulleys are selectively engaged, it is apparent that shafts 58 and 59, and therefore drums 60 and 61, are selectively operated in different directions.

The pulley 63' is connected to the shaft 59 in the manner best shown in Figs. 24 and 25. Herein it is shown that bosses 66 and 67 are mounted in diametrical relation on the spokes of the pulley 63'. These bosses have openings therein which are disposed in alignment with an opening 68 in the shaft 59. A resilient rod 69 extends through these aligned openings and is secured in the bosses 66 and 67 by pins 70. A similar construction is employed to attach pulley 63 to shaft 59 and also to attach pulleys 62 and 62' to shaft 58. Since the driving pulleys are provided at each end of the drums it is apparent that torsional strain thereon will be reduced to a minimum, and due to the resilient connection between the shafts and the pulleys shocks will be reduced to a minimum.

The mechanisms which carry the sets of prices are adapted to be carried by the drums 60 and 61. These mechanisms include the type carriers hereinafter referred to as the type bars 71. The type bars 71 are substantially U-shaped and extend across the machine so as to be of substantially the same length as the drums 60 and 61. In Figs. 8, 9, and 10 the construction of these type bars is shown. In the type bars 71, the type 72 and the spacers 73 are mounted. As best shown in Fig. 10, an elongated collar 74 is mounted at the end of the type bar 71. This

collar has an opening 75 extending therethrough. The bolt 76 extends through the opening 75 and the links 77 and 78 are disposed between the head portion 79 of bolt 76 and the ends of collar 74 and type bar 71. The links have openings therein through which the bolt 76 extends. The links 77 and 78 interconnect the ends of juxtaposed type bars 71, as best shown in Fig. 8, wherein it may be seen that the just described constructions are provided at both ends of the type bars. A nut 80 engages the screw threaded end of the bolt 76 and the inner end of collar 74 so as to hold the links in position. The inner end of bolt 76 is tapered and the wedge 81 is fitted thereunder. The type and spacers are forced into place so as to tightly secure the wedges in position, that is, the type and spacers are inserted before the end constructions, one spacer being omitted. This omitted spacer is shown in Fig. 10A and is comprised of two sections 82 and 83 which after insertion are forced against the walls of bar 71 by the set screw 84. This spacer is forced down after the parts are properly positioned and thus sufficient end thrust is created to hold these parts in position.

It is apparent from the foregoing that the links 77 and 78 connect the type bars so as to form a substantially chain like structure A. The ends of this structure are respectively connected to the drums 60 and 61. Rotatably supported at each side of the device, in the position shown best in Fig. 2, is a shaft 85 on which the drum 86 is mounted, Fig. 5. At the ends of drum 86 are sprockets such as 87 (Fig. 5). In the head portions 79 of bolts 76 are recesses 88. The type bar structure is guided around the drum 86 and the recessed portions 88 are engaged by the teeth of the sprockets 87. The path of the type bar structure A is best shown in Fig. 2 wherein it may be seen that guide rollers 89, supported by suitably mounted brackets 90, are provided.

Provided as part of the frame 53 is the structure 36 which extends upwardly at the front of the machine. Carried by the structure 36 are the brackets 91 (Fig. 2). Bearings are provided in these brackets and the shaft 92 is rotatably journaled therein. A sprocket 93 (Figs. 2 and 6) is provided on shaft 85 and provided on shaft 92 is a sprocket 94 which is aligned with sprocket 93. A chain 95 extends between the sprockets 93 and 94. The type bar structure A is coiled on the drums 60 and 61 and therefore when one drum is caused to revolve in a given direction the structure is withdrawn from one drum and wound on the other. As the structure A passes drum 86 the movement is transmitted to shaft 85 through the engagement of the teeth on sprocket 87 with the recesses 88. Movement of shaft 85 is transmitted to shaft 92 by the chain 95.

A plate 96 (Fig. 1) is carried by the structure 36 and rotatably mounted thereon are the sprockets 97. The sprockets 97 are mounted on the shafts 98 which are journaled in the bearings 99. The sprockets 97 are mounted as shown in Fig. 1 and a continuous chain 100 is directed around these sprockets. In addition to being directed around the sprockets 97 the chain 100 is directed across the device and around the corner sprockets 101 and is guided at opposite ends of the machine by suitable sprockets similar to the sprockets 101. A plate 103 is secured to the structure 36 and is disposed over the sprockets 97, 101, and chain 100. A slot 104 is provided in plate 103 and this slot is disposed so as to be contiguous the path of the chain 100 about the sprockets 97.

Bearings 105 (Fig. 4) are carried by the plate 96 and extend rearwardly therefrom. Shafts 106 are journaled in bearings 105 and sprockets such as 107 (Fig. 1) are mounted on one end thereof. The sprockets 107 mesh with chain 100. At the other end of shafts 106 bevel gears 108 are mounted and these gears mesh with bevel gears 109 on shafts 92. When shaft 92 is rotated, in the manner described, the movement thereof is transmitted to chain 100 through shaft 92, bevel gears 109 and 108, shafts 106, and sprockets 107. Thus, chain 100 is operated in a definite relation with and at the same time as the type structure A.

A pointer 110 is mounted on chain 100 and extends through slot 104. In Figs. 1, 13, and 14 it is shown that a plurality of indices 111 are mounted on plates 103. Channel members 112 are secured to plate 103 and the indices 111 are removably mounted therein. The indices are mounted in the same order as the sets of prices are mounted in the structure A. Therefore, since chain 100 moves with structure A the indicator 110 will point to an index which will correspond to a type bar which will be located in a position to be described. The foregoing describes the selecting mechanisms and now the mechanisms which cause the imprinting will be described.

In Fig. 3 it is shown that pulleys 113 and 113' are rotatably mounted on shafts 19 and 19'. These pulleys are suitably connected to gears 27 and 27' so as to be rotatable therewith. Belts 114 and 114' are led to the front of the machine and it is apparent that the pulleys 113 and 113' are continually operated, thus motivating the belts.

In Fig. 2 it is shown that the belt 114 is directed around pulley 115 which is fixed to the rotatably mounted shaft 116. Brackets such as 117 (Figs. 2 and 5) support brackets 118. The outer ends of shaft 116 are carried in the brackets 118 (Fig. 2). A bracket such as 119 (Fig. 16) supports a bracket 120 in which a stud shaft 121 is journaled. A gear 122 is mounted on shaft 116 which meshes with a

gear 123 mounted on stud shaft 121, (Fig. 16). Thus gear 122 and gear 123 are continually rotated.

A shaft 124 is mounted in the structure 36 and a plate 125 is suspended therefrom. A lock plate 126 (Fig. 17) is connected to the arm 127 which is pivotally mounted at 128 (Fig. 16) on the plate 125. The plate 126 has a recessed portion 129 in which one end of bar 130 is supported. The other end of bar 130 has a pin thereon which rides in slot 131 (Fig. 15) in bracket 119. In Figs. 19 and 20 it may be seen that bars 132 and 133 are juxtaposed bar 130. Slot 134 is provided in bar 133 and the pin 135, which is carried by the bar 130, extends therethrough. It is to be understood that the bars 130, 132, and 133 extend through an opening in plate 125 and this opening serves to hold the bars in position.

The bar 133 ends at substantially the point indicated in Fig. 19 and the bar 136 is pivotally secured thereto. Beyond the end of bar 133, a dog 137 is pivotally mounted on bar 130 and this mounting 138 tends to hold bars 130 and 133 together. The bar 136 is formed so as to have a portion thereof disposed above dog 137. A link 139 is pivotally secured to the end of the bar 136 and this link is also pivotally connected to dog 137 as at 140. A pin 141 on bar 130 engages the link 139, for a purpose to be brought forth. A pin 142 is mounted on the upper side of bar 132. A pin 143 is similarly mounted on bar 130 and a spring 144 extends between these two pins. A pin 145 is mounted on bar 130. A pin 146 is similarly mounted on bar 133 and a spring 147 extends between pins 145 and 146. An arm 148, Fig. 5, is pivoted on bracket 119 at 149 and is pivotally secured to arm 130 at 150, Fig. 16. A pin 151, to be described herein-after, is secured to bracket 120. A spring 152 extends between arm 148 and bracket 120 and acts against springs 144 and 147.

Referring again to Figs. 17, 19, and 20, it may be seen that a recess 153 is provided in the lower edge of bar 130. The lip 154 of an arm 155 is normally positioned in the recess 153. A spring 156 carried by plate 125 engages the lower end of lock plate 126 and holds lip 154 in recess 153. The bracket 127 is substantially L-shaped and on the end thereof opposite mounting 128 a key 157 is mounted. By depressing key 157 lip 154 is moved from recess 153. A recess 158 is provided in bar 132 and lip 159 of plate 126 enters this recess just prior to the time lip 154 disengages recess 153 and thus bar 132 is held against movement. The outer end of bar 133 normally bears against lock plate 126. When the lock plate 126 and arm 155 release bars 130 and 133 the spring 147 moves bar 133 forwardly through recess 129, as bar 130 is held against movement by spring 152, the parts being shown in normal position in Fig. 130

15. During this movement link 139 pivots about pin 140 and moves dog 137 downwardly.

As brought out heretofore the gear 123 is continually rotated. A cam 160 (Fig. 15) is fixed on gear 123 and is so positioned that when dog 137 is moved downwardly from the position in Figs. 15 and 19, the cam 160 will engage dog 137, and thus bar 130 is moved toward slot 131.

10 Bar 132 ends at 161. An angle plate 162 is positioned such that arm 163 thereof abuts the end of bar 132. A pin 164 is carried by bar 130 and extends through a slot 165 in arm 163. Normally pin 164 is at the opposite end of slot 165 from that shown in Fig. 16, but as arm 130 moves, the pin engages the end of the slot as shown and carries plate 162 therewith. This action is utilized in a manner to be described. A clamp plate 166 is secured to bar 130 and is disposed so as to enclose the ends of bar 132 and arm 163.

15 A shaft 167 is journaled in a bearing 168 (Fig. 2) and also in bearings on brackets 37, Fig. 5. A wheel 169 is mounted on shaft 167 and a pin 170 is eccentrically mounted thereon, Fig. 7. On arm 148 a link 171 is pivotally mounted which is urged downwardly by a spring 172, Fig. 16, the downward movement being limited by a shoulder 173. A wheel 174 is also mounted on shaft 167 on the inner side of wheel 169. Wheel 174 has a notch 175 in the periphery thereof in which a roller 176, carried on the forwardly projecting portion 177 of arm 148, is retained when the parts are in inoperative position.

20 When bar 130 moves rearwardly, arm 148, which is pivotally mounted on bracket 119 at 149 and also pivotally connected to bar 130 at 150, also moves rearwardly. Thus roller 176 is withdrawn from notch 175. A hook 178, Fig. 7, is provided at the outer end of link 171 which is adapted to engage the pin 170 and thus move wheel 169.

25 A wheel 180 is mounted on shaft 116 between pulley 115 and gear 122 and is continually rotated therewith. The periphery of this wheel includes a tire 181 of suitable material such as hard rubber. When the parts are in inoperative position a notch 182 Fig. 18, in the knurled periphery of wheel 169 is positioned such that wheel 180 will rotate past wheel 169 without moving said wheel. However, when wheel 169 is moved 30 as above described, the periphery thereof is brought into engagement with the periphery of wheel 180 and therefore shaft 167 will be set in motion.

35 It is apparent that dog 137 will engage cam 160 for only a part of a revolution. Therefore, when the dog 137 is released from cam 160 the roller 176 will spring back against the periphery of wheel 174. When the roller 176 falls into the notch 175, which, obviously, 40 will rotate wheel 174 into the position shown

in Fig. 16, the shaft 167 will again be held against movement and the notch 182 will again be positioned as shown in Fig. 7.

45 On shaft 167 interiorly of wheel 174 a gear 183 is fixed. The gear 183 meshes with a rack 184 on bar 185. Bar 185 is pivotally secured to arm 186 that is rotatably supported on shaft 85 in juxtaposition to sprocket 93. A member 187 extends upwardly from the base 10. A similar member 187', Fig. 21, also extends upwardly from base 10 and is disposed so as to provide a space between this member and member 187 and bar 185 extends into this space. A cam groove 188 is provided in members 187 and 187' and rollers 189 and 190 carried on bar 185 ride in these cam grooves. It is apparent that the groove 188 cuts away the center portion 191 of members 187. In order to support this portion 191 the brackets 192 and 193 are provided (Figs. 6, 15, 16, and 21). These brackets include an offset portion (see Fig. 21) which serves to permit the rollers 189 to pass without interference. A similar bracket construction is provided for the center portion of member 187'. As shown best in Fig. 21, a tubular spacer 194 is disposed between members 187 and 187' and a bolt 195 extends through this spacer, members 187 and 187', and the brackets 192 on these members. A similar construction is provided throughout the device for holding the brackets 192 and 193 in position. Links 196 and 197 (Fig. 15) extend between brackets 192 and 193 and a spacer 198 is disposed between the connection between these links and the portion 191. A bolt 199 extends through the spacer and is secured to portion 191 and links 196 and 197.

50 When shaft 167 is rotated as described, and therefore gear 183, it is apparent that the rack 184 and bar 185 are caused to travel upwardly, and during this upward travel the rollers 189 and 190 ride in groove 188. This action is utilized in a manner brought forth presently. As the rollers 189 and 190 approach the uppermost part of the cam groove 188, the lowermost part of the rack 184 will be meshing with gear 183. The teeth in this portion of the rack are foreshortened and this causes the rollers 189 and 190 to be moved into the downward directing portion of cam groove 188a. As will be described, the rack 184 acts to rotate arm 186 into a position on the line B of Fig. 6. When the rollers enter the downward directing portion of cam groove 188a, the rack 184 will be disengaged from gear 183, and will engage a roller 200 carried by a slideable bar 201 having a head 223 which will engage the notch 222 of the cam 221. This will be accomplished in the following manner:

55 When the arm 186 is in this position, the rollers 189 and 190 will be in portion 188a of the cam groove 188. At the juncture between portions 188a and 188b of the cam 180

100

105

110

115

120

125

groove 188 a pivotally mounted stop 202 is provided. As the roller 189 passes this stop, said stop is pivoted upwardly so as to permit said roller to pass and as soon as said roller is past the stop 202 falls back into the position shown in Fig. 6. When the stop is in this position, it will function to prevent the roller 189 from moving back into the portion 188a of the cam groove 188.

As has been stated heretofore, when the selective mechanisms function, a selected set of prices is positioned in a predetermined position and this position is indicated by the line D on Fig. 6. In Fig. 11 the construction of the arm 186 is depicted wherein it will be seen that a cylinder-like structure 203 is provided therein. A piston 204 is reciprocable in the cylinder 203. As best shown in Fig. 5, a ratchet 205 is mounted on the shaft 85 in juxtaposition to the sprocket 87. Adjacent the rear end of the cylinder 203 a fixed wall 206 is mounted which has an opening 207 therein through which the rod 208 is adapted to reciprocate. The rod 208 extends through and is secured to the piston 204. On the outer end of rod 208 is a pawl 209 which is adapted to engage the ratchet 205. A spring 210 is disposed within the cylinder 203 around the rod 208 and said spring extends between the wall 206 and the piston 204 and urges the piston 204 and therefore rod 208 and pawl 209 toward the ratchet 205. When the parts are in the position indicated in Figs. 6 and 11, the pawl 209 is engaging the ratchet 205. Therefore, when the arm 186 is elevated into a position on the line B on Fig. 6, the ratchet 205 and therefore shaft 85, will be moved and this movement will be sufficient to move the selective set of prices from the position on the line D on Fig. 6 into printing position which is indicated by the line P on Fig. 6. At the time the arm 186 attains the position on the line B on Fig. 6 a lug (not shown) carried by the structure 36 engages the frictionally retained slide 211 which is mounted in the arm 186 and said lug moves the slide 211 downward. On the rod 208 between pawl 209 and piston 204 the member 212 is mounted which has a cam surface 213 thereon which is adapted to be engaged by the upwardly projecting cam follower portion 214 of slide 211. Therefore, when slide 211 is moved downwardly, the portion 214 moves over the cam surface 213 and retracts the pawl from engagement with the ratchet 205. Therefore, when the arm 186 moves downwardly to the position on line C on Fig. 6, the stop plug 215 carried by structure 36 will force the slide 211 upwardly so as to disengage the lower portion 214 from the cam surface 213 so as to permit the pawl 209 to re-engage the ratchet 205. The foregoing mechanisms serve to properly position the selected set of prices in printing position.

As illustrated in Fig. 6, the bar 201 is slid-

ably carried by an arm 216, and this slidable connection is accomplished by the pin and slot connection 217. The arm 216 carries a plate 218 and this plate 218 is pivotally connected to the arm as at 217'. The plate 218 is normally held in alignment with the arm 216 by a spring 215', Fig. 6. When the arm 186 is in the position on the line B on Fig. 6, roller 200 of the bar 201 will be positioned such that the rack bar 185 will strike said roller when said bar 185 moves downwardly and this action is utilized in the manner now to be described.

As shown in Fig. 2, the bracket 118 has a bearing 219 therein in which one end of the shaft 220 is journaled. The shaft 220 is also journaled in bearings provided in the heretofore mentioned brackets 37. On the shaft 220 is a cam 221 which has a notch 222 formed on one portion of the periphery thereof. This notch 222 is adapted to be engaged by the end 223 of plate 218 of the bar 201 when said plate 218 is moved in the manner just described. This movement is sufficient to impart a slight movement to the shaft 220. The notch 222 is permitted to pass over the end 223 by depressing the plate 218 against the action of the spring 215'. Fixed on the shaft 220 in alignment with the wheel 180 is a wheel 224 which has a notch 225 in the periphery thereof substantially similar to the notch 182 in the periphery of wheel 169. When shaft 220 is moved in the manner just described, the notch 225 is moved from the position depicted in Fig. 6 into a position such that the knurled periphery of wheel 224 will engage the tire periphery of wheel 180. Inasmuch as wheel 180 is continually rotating, it is apparent that shaft 220 will be rotated a complete revolution until notch 225 is repositioned in the position shown in Fig. 7.

Referring now to Figs. 18 and 5, it may be seen that blocks 226 are carried by the base 10 and said blocks are disposed near the front of the machine substantially below each side of shaft 85. On the upper side of the blocks 226 two trackways 227 and 228 are provided. The blocks 226 are cored out so as to reduce weight, and disposed so as to form a center rib are the portions 229. In the upper part of the portions 229 the keyways 230 are provided in which the keys 231 are fixed. A substantially circular track 232 has keyways 233 therein in which the keys 231 are fitted so as to support the track 232. Carriages such as 234 are provided to travel on the tracks 227 and 228 on block 226, Fig. 18. The carriage 234 is arranged so as to embody a central opening 237 and rotatably mounted on a suitable shaft in this opening is the wheel 238 that is adapted to travel along the track 232. A supporting bed 239 is secured above the carriage 234 and brackets 240 are disposed between the supporting bed 234 so as to increase the rigidity of the supporting bed.

At the ends of the supporting bed and at spaced apart points therealong, angle plates such as 241 and 242 are secured to the supporting bed 239 as by the bolts 243. As shown best in Fig. 18, a rectangular recess 244 is provided in the upper part of the plate 241 and similar recesses are provided in the other of the similar plates. Disposed so as to be supported on the lower edge of these recesses is a bar 245 (Figs. 5, 18, 22 and 23) and at spaced apart intervals along the bar 245 are pins 246 which extend laterally therefrom. A bar 247 is disposed above the bar 245 and is co-extensive therewith. Plates 248 are secured to the sides of bar 247 and have recesses 249 therein through which the pins 246 are adapted to extend. In the lower edge of the bar 247, substantially keystone shaped notches 250 are provided. Secured to the upper side of bar 245 as by rivets 251, are leaf springs 252 which are so disposed that ends thereof are mounted in the corners of the notches 250. The leaf springs 252 act on the bar 247 in such a manner as to force said bar 247 away from the bar 245 and this action is limited by the engagement of the pins 246 with the lower edges of the slots 249. It is therefore apparent that the bar 247 is resiliently supported. The bar 247 is adapted 30 to be disposed substantially on the line P of Fig. 6.

In addition to the pins 246 pins 246a (Fig. 5) are provided so as to extend laterally from the bar 245. Disposed to extend 35 between the pins 246a and the pins 246 which are juxtaposed the ends of bar 245, are coil springs 253 and the lower ends of these springs are secured to pins 254 and 254a which are carried by the brackets 241 and 40 242. The coil springs 253 act to hold the bar 245 against the lower edges of the recesses 249. The bar 245 is disposed so as to extend just above the shaft 220.

At spaced apart intervals on the shaft 220 45 cams 255 are mounted. The cams 255 are arranged so that they will occupy substantially the position shown in Fig. 6 when they are in inoperative position. However, when the shaft 220 is rotated in the manner heretofore described, the upwardly extending portions 256 of the cams 255 engage the bar 245 and move said bar upwardly through the recesses 249. Obviously this also raises the bar 247. In a manner hereinafter described, the accounting statement such as that illustrated in Fig. 12, is fed into a position between the set of prices which will have been moved onto the line P of Fig. 6 and the bar 247. Therefore, when bar 247 is moved 50 60 upwardly the accounting statement is forced into engagement with the selected set of prices and inking ribbons are disposed between the prices and the accounting statement and therefore the prices will be im- 65 75 80 85 90 95 100 105 110 115 120 125 130

bons and the constructions controlling their operation will now be described.

As is shown best in Fig. 18, arm 257 extends upwardly from the plate 241 and is carried thereby. The laterally extending arm 258 is secured to the upper end of arm 257 and the arm 258 includes an offset portion 259 which is disposed so as to prevent interference of said arm with the shaft 85. The downwardly extending portion 179 of a plate 260 is secured to the arm 258 by means of rivets 39 in the manner best shown in Fig. 18. The plate 260 includes a portion 261 which is looped about the shaft 124 so as to be supported therefrom and slidable therealong. Brackets 262 (Figs. 1 and 4) are secured to the plate 260 and extend outwardly therefrom. In the outer ends of the brackets 262 notches 263 are provided in which a shaft 264 is removably mounted. Mounted on the shaft 264 in any approved manner so as to be shiftable therealong are the spools 265 on which the inking ribbons 266 are adapted to be wound. It is apparent that the inking ribbons 266 are supported so as to be movable with the carriage 234, and therefore these ribbons are shiftable with respect to the sets of prices in the structure A. The lower end portion 267 of plate 260 (Fig. 18) is disposed so as to guide the inking ribbons 266 around and past the structure A as it passes the pulley 87 and so as to dispose these ribbons above the bar 247.

As is most clearly shown in Fig. 18, a notch 268 is provided in the upper part of the bracket 119. The arm 258 terminates at a point directly above this notch and a downwardly extending bracket 269 is carried at the end of the arm 258 and includes a loop portion 270 which is adapted to be disposed in alignment with the circular portion of notch 268. It is to be understood that an arm similar to arm 258 is provided on the opposite side of the machine and that a bracket 269 is also carried by this arm. A shaft 271 is 110 rotatably journaled in the loops 270 and mounted thereon so as to be disposed in alignment with the spools 265 are ribbon receiving spools 272. As the shaft 271 is moved with a step by step movement to be described presently, the inking ribbons are withdrawn from the spools 265 and are wound on the spools 272.

The step by step movement imparted to shaft 271 is obtained in the following manner. A ratchet wheel 273, Figs. 16 and 5, is mounted on shaft 271 in such a position that the pawl arm 274 of angle plate 162 will engage the teeth thereof when the angle plate 162 is moved in the manner heretofore described. As clearly shown in Figs. 16 and 20, the pawl arm 274 is elongated and this construction is provided since the ratchet wheel 273 will be shifted along with carriage 234. In Figs. 16 and 20 it is shown

that a pin 275 is carried by arm 163 and a pin 276 is carried by bar 132. A spring 277 is disposed between these pins which tends to hold bar 132 and arm 163 in abutment at 161. When arm 163 and therefore pawl arm 274 are moved in the manner described, the pawl arm 274 engages the teeth of ratchet wheel 273 and therefore rotates ratchet wheel 273 and shaft 271 an amount sufficient to impart a slight rotary movement thereto so as to retract some of the inking ribbons 266 from the spools 265. Inasmuch as the spools 265 are mounted on the front of the machine in plain view of the operator, said operator 10 may readily see when the inking ribbons 266 have been withdrawn from the spools 265. Therefore, by manipulating the hand wheel 278 on shaft 264, the inking ribbons may be again wound on the spools 265.

Supported from base 10 in any approved manner is the stationary plate 279 (Fig. 1) which lies between the paper coiling portions 280. The head end of the accounting statement is fed into the paper coiling portion 280 over the lip 281 thereof and then is brought out along the portion 282 and is slipped under the guide plate 283 (Fig. 1) that is carried by the base 10. Since the paper coiling portions 280 are suitably mounted on angled plates 241, it is apparent that these plates are shiftable relative to the structure A, and therefore since the accounting statement is carried thereby, said statement will also be shifted. The spring clips 284 are carried by the paper coiling portion 280 so as to effectively retain the statement in position and slots 285 are provided in the plate 279 so as to permit the clips 284 to slide along relative to the plate 279 without 30 interference therewith. As is shown best in Fig. 18, the stationary plate 279 includes a guiding portion 286 which directs the paper to printing position and this portion 286 terminates just in front of said printing position.

Secured to the plate 96 is downwardly extending bracket 287 which includes foot portions 288 which are suspended above and near the stationary plate 279. As is best illustrated in Fig. 1, the foot portions 288 have smooth bottom surface 289 thereon and are suspended just above openings 290 which are provided in the plate 279. On the inner side of plate 279 and extending downwardly 50 therefrom are bearing brackets 291, in which a shaft 292 is rotatably journaled. A sprocket 293 is mounted on shaft 292 and a sprocket 294 is mounted on shaft 220 in alignment with said sprocket 293. A chain 295 extends between the sprockets 293 and 294 and therefore when shaft 220 is rotated, shaft 292 is also rotated. Mounted on shaft 292 below the openings 290 are eccentric discs 296 which have hard rubber peripheries. 60 The discs 296 are eccentric and in inoperative

position are disposed so that no portion of the periphery thereof extends through the openings 290, (Fig. 18). It is apparent that the accounting statement will be inserted underneath the foot portions 289. Therefore, 70 when shaft 292 is rotated, the raised portions of the eccentric discs will extend through the openings 290 and will engage the under side of the accounting statement against the bottom surfaces 289 and carry said statement 75 forward. An index such as 297 may be provided on one of the foot portions 288 and the line on which the imprinting is to be done will be disposed in alignment with this index. This index will be so located that the 80 line in alignment therewith will be moved into the position indicated by the line P on Fig. 6 upon one rotation of the eccentric discs 296.

Disposed so as to be connected to the carriage 234, Figs. 1 and 2, are downwardly extending arms 298, Fig. 1, and these arms carry at their outer ends the rack 299 which is in alignment with and meshes with gear 300. The clamping structure 301 includes a 90 shaft 38 mounted thereon on which gear 300 and the levers 302 are rotatably secured. By manipulation of the levers 302, the carriage 234 and its allied parts are adapted to be retracted as heretofore described.

In the plate 260 an opening 304, Fig. 1, is provided which has an index 305 co-operating therewith. The opening 304 is so disposed that the selected set of prices on the line D of Fig. 6 will lie just below the indexes 305 and therefore the selected set of prices may be viewed at this point.

As is clearly shown in Fig. 5, the shafts 116, 167 and 220 extend across the machine. Appurtenances such as those described as being mounted on and operated by the shafts, are provided on both sides of the machine. As is readily apparent by referring to Fig. 3, a pulley 113 is provided opposite the gear 27 and this pulley serves to drive a pulley 115, similar to the pulley 115', which is disposed on the opposite end of the shaft 116. As is clearly illustrated in Fig. 1, two keys 157 are provided on opposite sides of the machine, and therefore bar structures such as 130, 132, and 133 are also provided on opposite sides of the machine. Therefore, by depressing either of the keys 157 the mechanism on both sides of the machine will simultaneously be set in operation.

A summation of the operation of the device thus far described is as follows: The accounting statement will be inserted into the holder therefor and will be slipped around until the item on the first line thereof is in alignment with the index 297. The motor 11 will be operating and therefore when operator has ascertained that the set of prices desired is for part number A—108, Fig. 12, said operator will manipulate either lever 42 or 42' to engage 125 130

the desired pulley. The selection of this pulley will depend upon the location of index 110, Fig. 1, and the device will be caused to run in the direction which will most quickly bring the index 110 to bar A—108. This optional direction of operation is afforded by the structure heretofore described for operating the structure A.

When the index 110 is in register with the number A—108 on the selection board, the index 305, Fig. 1, will also be registering with A—108 which will be positioned therebelow. As is clearly illustrated in Fig. 8, all of the type bar structures have provided thereon a direct reading index which is indicated at the point S, and this index at the point S is the one that will register with the index 305. When this operation has been completed, the selected set of prices will lie on the line D on Fig. 6.

The operator will next depress key 157 which will release the bars 130, 132 and 133 which will function in the manner heretofore described; that is, the dog 137 will be positioned so as to be engaged by the cam 160 and therefore bar 130 will be moved rearward. During the rearward movement of bar 130, pawl arm 274 will engage the teeth of ratchet 273 and will advance the ribbons as heretofore described. At this same time, arm 148 will retract roller 176 from notch 175 and hook 178 will engage pin 170 so as to impart sufficient movement to disc 169 so as to bring the periphery thereof into engagement with the periphery of wheel 180. Therefore, shaft 167 will be rotated one complete revolution which will cause the advancing mechanisms which include rack 184, to function. This will move the set of prices for part number A—108 into printing position on line P of Fig. 6. As soon as the parts are in this position, the bar 185 will strike the roller 200 which will thus cause the end 223 of the bar 201 to engage the notch 222, and thus impart sufficient movement to shaft 220, to bring the periphery of wheel 224 into engagement with the periphery of wheel 180 and thus shaft 220 will be set in operation. Movement of shaft 220 will be imparted to shaft 292 and thus discs 296 will move the accounting statement into printing position and at the time the line bearing number A—108 is disposed on the line P of Fig. 6, the cams 255 will act to force bar 247 upwardly so as to imprint the prices on the sheet.

The type and ribbons will be so disposed that the part number will be imprinted under the heading of code which is blank on the accounting statement and proper figures will be imprinted under the headings of price, class and cost. It is apparent that this positioning will be obtained by varying the relative position of the spacer 73 in the type.

After this operation has been completed, the paper will be retracted so as to align the

second item on the accounting statement with the index 297.

Again referring to Fig. 12, it may be seen that a second item on the accounting statement, as depicted therein, is part number S—27. By referring to Fig. 1, it may be seen that the index for part number S—27 is located at the other end of the device from the index for the part number A—108. It is to be understood however, that even though this part number will have been imprinted last, the index 110 will not be positioned thereabove for when the positioning devices, which include the rack 184 and the allied appurtenances, will have functioned, the index 110 will have been moved an amount equal to the movement from the line D to the line P on Fig. 6. Therefore, the operator, by again manipulating handle 42 or handle 42', may cause certain of the pins 40 to enter the co-operating recesses 41 so as to clutch the selected pulley to the proper gear and thus drive structure A. It is apparent that in the present instance part number S—27 will be reached by running the index 110 in an upward direction from its present position. As soon as the index 110 registers with index S—27, the operating handle is released which causes pulleys and gears to assume a relatively disengaged position. Therefore, by again depressing the key 157, the mechanism will operate in the manner heretofore described and will thus cause the proper prices to be imprinted on the second line of the accounting statement on which the part number S—27 has been imprinted.

The operator will again retract the accounting statement so as to align it with the index 297 and therefore it will be determined that the part number S—27 is again required. It is apparent that it will be necessary to again operate the handle 42 so as to retract the index 110 into register with the index S—27. In order to obviate this operation I provide the following construction.

Referring again to Figs. 15, 16, 19 and 20, it will be noted that the bar 132 is arranged so as to have pin and slot engagement with the bars 130 and 133. As has been described heretofore, when the key 157 is depressed the bar 132 is held against movement by the lip 159. Bar 132 terminates at its outer end and in an upwardly extending portion 306 a key 307 is mounted. Therefore, by pushing key 307 which is held in position only by spring 144, bar 132 may be moved rearwardly and bars 130 and 133 will be held against movement by the lip of arm 155. This rearward movement of bar 132 will be imparted to arm 163 and will cause pawl arm 274 to engage ratchet 273 and thus impart movement to the ribbons in the manner heretofore described. A pin 308 is provided on wheel 221 and an outwardly extending clip 309 is provided on bar 132, Fig. 1. When bar 132 is moved rear-

wardly pin 308 engages the outwardly extending lip 310 of the clip 309 and therefore sufficient movement is imparted to shaft 220 to cause the engagement of the periphery of wheel 224 with the periphery of wheel 180. 5 Therefore the printing mechanisms which include the cams 255 will function. It is apparent that the positioning members which include the rack 184 will not function and only the paper advancing and printing mechanisms will function. 10 After operator has carried out the above operation the statement will be retracted so as to bring the next line thereon into alignment with the index 297 and operator will determine that the part number A—100 is next desired and therefore parts will be operated in the manner heretofore described.

As stated the device functions so as to imprint the code or part number under the column headed code in which no figures are originally imprinted. Therefore, when it is desired to check the statement to see if it has been properly priced before the extensions are made, it is merely necessary to check the two parts under the headings of code, and if these parts coincide, it is readily apparent that the prices imprinted will be proper since these prices will be checked at the time the 25 type is positioned.

It is readily apparent that there might be a variation in the vertical alignment of the accounting statements. It is to take care of such a situation that I have provided the 30 rack 299 and the co-operating appurtenances. By gripping the handles 302 and moving said handles one way or the other, the gear 300 to rotate in rack 299, and therefore the appurtenances carried on the carriage 234, 35 which include the accounting statement, may be shifted relative to the type in the structure A and therefore imprinting at the proper points is assured.

In order that the device may be manually 40 operated, I provide a square portion 325 on the end of shaft 85 to which a suitable handle may be attached, Fig. 5.

The indices are conveniently located by means of a locating rod 326 on which is 45 mounted in any suitable manner finger buttons 327. The ends of the rod 326 are mounted in suitable bearings 328 carried by bars 329 slidably mounted in sleeves 330 fixed to the frame structure in any suitable manner. 50 Connected to the bearings 328 are cables 331 or the like which project over suitable pulleys 332, Fig. 2, toward the rear of the machine and carry at their end portions suitable weights 333, which weights function to 55 balance the rod in an adjusted position.

If desired suitable brake mechanism (not shown) may be associated with the rod 326 to be operated by movement of the indicator 110 whereby to stop operation of the machine.

65 While I have illustrated and described the

preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what 75 I claim as new and desire to protect by Letters Patent is:

1. In a device of the class described, a frame having bearings therein, shafts journaled in said bearings and disposed in parallel relation, drums freely mounted on said shafts, power receiving means freely mounted on said shafts and fixedly secured to the ends of said drums, means for yieldably connecting power receiving means to said shafts, 80 a plurality of type carrying bars, means for connecting said bars into a substantially chainlike structure, means for connecting the respective ends of said structure to said drums whereby said structure may be wound upon said drums so as to be windable from one to the other, and means connected to said power receiving means whereby either of said drums may be selectively driven so as to withdraw said structure from the other 85 of said drums for winding upon said driven drum.

2. In a device of the class described, a frame having bearings therein, shafts journaled in said bearings and disposed in parallel relation, drums freely mounted on said shafts, power receiving means freely mounted on said shafts and fixedly secured to the ends of said drums, means for yieldably connecting power receiving means to said shafts, 100 a plurality of type carrying bars, means for connecting said bars into a substantially chainlike structure, means for connecting the respective ends of said structure to said drums whereby said structure may be wound upon said drums so as to be windable from one to the other, a motive means, means disposed adjacent said motive means having members thereon adapted to be driven in opposite directions, and means having driving connection with said power receiving means adapted to be selectively connected to either of said oppositely rotating members whereby one 105 of said drums may be driven so as to withdraw said structure from the other of said drums for winding upon said driven drum.

3. A device of the class described including means having a plurality of sets of type mounted therein, means adapted to support said type carrying means for winding and 120 unwinding movement, means having a plurality of indices mounted thereon arranged in relative relation with said sets of type, and means connected to said type carrying 125 means and adapted for synchronic movement 130

therewith and having a pointing means thereon adapted to register with said indices whereby it may be determined when a selected set of prices are in a predetermined position.

5 4. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a drum carried by said frame and disposed such that said structure is directed therearound, sprockets on said drum, means on said structure adapted to engage said sprockets whereby to rotate said drum, and means connected to said drum adapted to indicate the relative position of said type bars in respect to said drum.

10 5. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a drum carried by said frame and disposed such that said structure is directed therearound, sprockets on said drum, means on said structure adapted to engage said sprockets whereby to rotate said drum, a structure having a plurality of indices thereon arranged in relative relation to the type bars in said chain-like structure, means including a pointer adapted to register with said indices and synchronically connected to said last named drum whereby said pointer will register with the index on said structure which corresponds to the type bar disposed in a predetermined position relative said last named drum.

15 6. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a rotatably mounted drum disposed such that said chainlike structure is directed therearound, means for imparting movement of said structure to said drum, and means synchronically connected to said drum adapted to indicate which of said type bars is in a predetermined position.

position relative to said last named drum when movement of said structure is halted.

7. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a rotatably mounted drum disposed such that said chain-like structure is directed therearound, means for imparting movement of said structure to said drum, means synchronically connected to said drum adapted to indicate which of said type bars is in a predetermined position relative to said last named drum when movement of said structure is halted, and a constantly rotated shaft, a shaft juxtaposed said shaft, means for connecting said last named shaft to said first named shaft whereby said last named shaft will be imparted one revolution, and means operated by said last named shaft for moving said type bar in said predetermined position into printing position.

8. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a rotatably mounted drum disposed such that said chain-like structure is directed therearound, means for imparting movement of said structure to said drum, means synchronically connected to said drum adapted to indicate which of said type bars is in a predetermined position relative to said last named drum when movement of said structure is halted, and a constantly rotated shaft, a shaft juxtaposed said shaft, means for connecting said last named shaft to said first named shaft whereby said last named shaft will be imparted one revolution, means operated by said last named shaft for moving said type bar in said predetermined position into printing position and another shaft juxtaposed said constantly rotated shaft, and means adapted to be actuated by said last named moving means adapted to connect said last named shaft to said constantly rotated shaft whereby said shaft will be rotated one revolution, and means for causing said type to imprint adapted to be actuated by said shaft.

9. In a device of the class described, a

pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a rotatably mounted drum disposed such that said chain-like structure is directed therearound, means for imparting movement of said structure to said drum, means synchronically connected to said drum adapted to indicate which of said type bars is in a predetermined position relative to said last named drum when movement of said structure is halted, and a constantly rotated shaft, a shaft juxtaposed said shaft, means for connecting said last named shaft to said first named shaft whereby said last named shaft will be imparted one revolution, means operated by said last named shaft for moving said type bar in said predetermined position into printing position and another shaft juxtaposed said constantly rotated shaft, and means adapted to be actuated by said last named moving means adapted to connect said last named shaft to said constantly rotated shaft whereby said shaft will be rotated one revolution, means for moving an accounting statement or the like into printing position adapted to be actuated by said shaft, and means for causing said type to imprint on said statement adapted to be actuated by said shaft.

10. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a rotatably mounted drum disposed such that said chain-like structure is directed therearound, means for imparting movement of said structure to said drum, and means synchronically connected to said drum adapted to indicate which of said type bars is in a predetermined position relative to said last named drum when movement of said structure is halted, means for moving said type bar in said predetermined position into printing position including a constantly rotated shaft, a shaft juxtaposed said shaft, means for connecting said last named shaft to said constantly rotated shaft for one revolution therewith, means for moving an accounting statement or the like into printing position adapted to be actuated by said shaft, and means for causing said type to imprint on said statement adapted to be actuated by said shaft, and means for caus-

ing said type to imprint on said statement adapted to be actuated by said shaft.

11. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a rotatably mounted drum disposed such that said chain-like structure is directed therearound, means for imparting movement of said structure to said drum, and means synchronically connected to said drum adapted to indicate which of said type bars is in a predetermined position relative to said last named drum when movement of said structure is halted, means for moving said type bar in said predetermined position into printing position including a constantly rotated shaft, a shaft juxtaposed said shaft, means for connecting said last named shaft to said constantly rotated shaft for one revolution therewith, means for moving an accounting statement or the like into printing position adapted to be actuated by said shaft, inking ribbons disposed between the type in said bar and said statement, means for moving said ribbons, and means for causing said type to imprint on said statement through said ribbons adapted to be actuated by said one revolution shaft.

12. In a device of the class described, a pair of rotatably mounted drums, a plurality of type bars, means for connecting said type bars to form a substantially chain-like structure, means for connecting the ends of said chain-like structure to said drums whereby said structure may be wound upon said drums, means for selectively driving either of said drums whereby said structure may be withdrawn from the other of said drums for winding upon said driven drum, a rotatably mounted drum disposed such that said chain-like structure is directed therearound, means for imparting movement of said structure to said drum, and means synchronically connected to said drum adapted to indicate which of said type bars is in a predetermined position relative to said last named drum when movement of said structure is halted, means for moving said type bar in said predetermined position into printing position, inking ribbons disposed below the type in said type bar, means for supporting said inking ribbons adapted to be shifted relative to said type bar, members on said last named means adapted to support an accounting statement or the like, means for moving said accounting statement into printing position below said type and said ribbons, and means for forcing said statement into engagement with said rib-

bons and said type so as to cause said type to imprint thereon.

13. In a printing device, means for moving sets of type into printing position, means shiftable relative to said type adapted to carry the blank to be imprinted and the ribbons adapted to supply the printing medium, and means for locking said shiftable means in position.

10 14. Machine of the class described, comprising synchronized rotative drums, chain of type-carrying bars alternately windable upon and off said drums, means for selecting a set of type from said bars, means bearing 15 indices, and pointing means having synchronized movement with said chain for indicating upon said indices the position of a selected set of type in said chain.

15. Machine of the class described, comprising synchronized rotative drums, chain of type-carrying bars alternately windable upon and off said drums, means for selecting a set of type from said bars, means bearing indices, pointing means having synchronized 20 movement with said chain for indicating upon said indices the position of a selected set of type in said chain, and means for imprinting said selected set of type.

16. Machine of the class described, comprising synchronized rotative drums, chain of type-carrying bars alternately windable upon and off said drums, means for selecting a set of type from said bars, means bearing indices, pointing means having synchronized 30 movement with said chain for indicating upon said indices the position of a selected set of type in said chain, and a shiftable carriage for positioning record bearing material in printing position relative to said 35 selected set of type.

17. Machine of the class described, comprising synchronized rotative drums, chain of type-carrying bars alternately windable upon and off said drums, means for selecting a set of type from said bars, means bearing indices, pointing means having synchronized movement with said chain for indicating upon said indices the position of a selected set of type in said chain, and a shiftable carriage for positioning record bearing material in printing position relative to said selected set of type, and means for advancing inking means between said selected set of type and record bearing material.

55 18. Posting machine, comprising synchronously rotative drums, a chain of type-carrying bars alternately windable upon and off said drums, means for selecting a set of type from said bars, means bearing indices, pointing means having synchronous movement with said chain for indicating upon said indices the position of a selected set of type, and means for imprinting said selected set of type on record bearing material.

65 19. Posting machine, comprising synchro-

nously rotative drums, a chain of bars carrying a plurality of sets of types and windable alternately upon and off said drums, indices, pointing means movable with said chain for indicating upon said indices the position of a selected set of said type, and a shiftable carriage for positioning record bearing material in printing position relative to a selected set of type and inking means.

In testimony whereof I affix my signature.

FRED W. LA CHANCE.
